GRINDING WHEEL SPINDLE RECIPROCATING APPARATUS

Charles C. Alvord, Worcester, Mass., assignor to
Norton Company, Worcester, Mass., a corpora-
tion of Massachusetts

Application June 8, 1939, Serial No. 278,123

1 Claim. (Cl. 51—34)

This invention relates to grinding machines, and more particularly to a grinding wheel spindle reciprocating mechanism.

One object of the invention is to provide a simple and thoroughly practical mechanism for reciprocating a grinding wheel spindle axially within its bearings. Another object of the invention is to provide a grinding machine with a spindle reciprocating mechanism, in which the grinding wheel spindle may be oscillated or reciprocated through an adjustable stroke. Another object is to provide a wheel spindle reciprocating mechanism which is driven independently relative to the spindle drive, and which is provided with adjusting means whereby the reciprocatory stroke of the spindle may be varied during rotation of the wheel spindle. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claim.

In the accompanying drawings, in which is shown one of various possible embodiments of the mechanical features of this invention,

Fig. 1 is a vertical sectional view through a grinding machine wheel slide showing the wheel spindle reciprocating mechanism;

Fig. 2 is a horizontal sectional view, on an enlarged scale, taken approximately on the line 2—2 of Fig. 1;

Fig. 3 is a fragmentary sectional view taken approximately on the line 3—3 of Fig. 1;

Fig. 4 is a fragmentary sectional view taken approximately on the line 4—4 of Fig. 1, showing the mechanism for adjusting the length of the grinding wheel reciprocatory stroke;

Fig. 5 is a fragmentary cross sectional view taken approximately on the line 5—5 of Fig. 2;

Fig. 6 is a fragmentary sectional view taken approximately on the line 6—6 of Fig. 1, showing the length of the reciprocatory stroke of the grinding wheel;

Fig. 7 is a fragmentary sectional view taken approximately on the line 7—7 of Fig. 1; and

Fig. 8 is a cross sectional view taken approximately on the line 8—8 of Fig. 7.

A grinding machine has been illustrated in the drawings comprising a base 10 which supports a transversely movable wheel slide 11 on a V-way 12 and a flat way 13 on the base 10. The wheel slide 11 supports a rotatable grinding wheel

which is mounted on one end of a rotatable wheel spindle 16. The spindle 16 is journaled in suitable bearings 17 and 18 within the wheel slide 11. The right-hand end of the wheel spindle 16 (Fig. 1) is provided with a driving pulley 19 which is preferably of a multiple V-grooved type. The wheel spindle 16 may be driven in a manner to be hereinafter described.

A wheel feeding mechanism is provided for manually feeding the grinding wheel 15 toward and from the work piece, which comprises a half nut 22 depending from the under side of the wheel slide 11. The half nut 22 meshes with or engages a rotatable cross feed screw 23 which may be rotated by any of the well known wheel feeding mechanisms such as, for example, that shown in the expired United States patent to C. H. Norton No. 762,838 dated June 14, 1904. This mechanism has not been illustrated in detail in the present application since it is not considered to be a part of the present invention. Consequently, for further details of construction, reference may be had to the above-mentioned prior patent.

A grinding wheel driving mechanism is provided whereby the grinding wheel 15 may be rotated at a normal grinding speed either for a grinding operation or for a grinding wheel truing operation, or the wheel may be rotated at a very slow speed below the normal grinding speed for a polishing operation, or the grinding wheel may be held against rotation for a honing operation and automatically indexed after each successive honing operation to present a new abrading surface for the next operation.

The grinding wheel 15 is preferably driven by a motor driven mechanism comprising an electric motor 25 which is mounted on an adjustable support 26. The adjustable support 26 is provided with a dovetailed slideway 27 which mates with a correspondingly shaped way on top of a casing 28 which supports the gear driving mechanism. The casing 28 is adjustably mounted on the upper surface of the wheel slide 11. The motor 25 is preferably a variable speed motor, such as a DC motor which receives its power from the power lines 29. As diagrammatically illustrated, a switch 30 serves to stop and start the motor 25, and a speed control device, which is diagrammatically illustrated as a rheostat 31, serves to adjust and vary the speed of the motor 25. The motor 25 is provided with a driving belt which is connected by means of a multiple V-belt 32 with a multiple V-grooved pulley 33 mounted on the outer end of a motor shaft 34. The V-belts 32 are connected with a V-grooved pulley 35 mount-

ed on the outer end of a shaft 36 which is journaled in a bearing 37 in the casing 28. The inner end of the shaft 36 is keyed within a sleeve or bushing 38 which is in turn rotatably supported by anti-friction bearings 39 which are also supported by the casing 28. The sleeve 38 also supports a bearing bushing 40 which serves as a bearing support for a rotatable shaft 41. The outer end of the shaft 41 is journaled in a bearing 42 carried by the casing 28. A multiple 10 V-grooved driving pulley 43 is mounted on the outer end of the shaft 41 and is connected by multiple V-belts 44 with the multiple V-grooved pulley 19 mounted on the outer end of the wheel spindle 16.

An adjusting screw 48 is rotatably supported in a bearing 49 which is either formed integral with or fixedly mounted on the casing 28. The screw 48 is held against endwise movement relative to the bearing 49 and the screw 48 meshes with or engages a nut 50 depending from the under side of the motor support 26. By adjusting the screw 48, the position of the motor mounting 26 may be adjusted so as to properly tension the driving belt 44. A similar adjustment is provided for the casing 28. A dovetailed slideway 52 is formed between the casing 28 and the wheel slide 11. A similar nut and screw adjustment is provided between the casing 28 and the wheel slide 11 by means of which the multiple V-belt 32 may be tensioned as desired.

In order to obtain a fast speed of the grinding wheel 15 for a normal grinding operation or for turing the grinding wheel, it is desirable to provide a suitable connection whereby the shaft 36 may be connected directly with the shaft 41. The slidably mounted clutch 55 is slidably keyed onto the shaft 41. The clutch 55 is moved toward the left (Fig. 2) so that the clutch teeth 56 of the slidably mounted clutch member 55 engage clutch teeth 57 formed in the end of the rotatable sleeve 38 which is keyed to the shaft 36 so that power is transmitted directly from the shaft 36 to the shaft 41 and through the pulley 43 and multiple V-belts 44 to rotate the wheel spindle pulley 19, the wheel spindle 16, and the grinding wheel 15 at a normal, relatively fast grinding speed.

The clutch member 55 is preferably arranged so that it may be readily controlled from the operator's station in front of the machine. A yoked member 60 is supported on a rock shaft 61 which is journaled in bearings 62 and 63 in the housing or casing 28. The lower end of the yoked member 60 is provided with opposed studs 64 which ride in a groove 65 formed in the periphery of the clutch member 55. The shaft 61 is provided with a gear segment 66 which meshes with a gear segment 67 carried by the shaft 68 which is rotatably journaled in a bearing 69 formed in the casing 28. The outer end of the shaft 68 is provided with a manually operable actuating handle 70. Formed integral with the gear segment member 66 is a downwardly extending arm 71 which is provided with a pair of apertures 72 and 73 which are arranged to be engaged by means of a spring-pressed detent such as a ball 74 to readily locate the gear segment 66 in one of two positions, namely with the clutch teeth 56 in engagement with the 70 clutch teeth 57 or with clutch teeth 76 in engagement with clutch teeth 77 formed integral with a rotatable bushing 78 which forms a part of a slow speed driving mechanism to be hereinafter described. As shown in Fig. 2, the clutch 75

55 is in a slow speed position. If it is desired to rotate the grinding wheel 15 at a fast speed, that is, the normal grinding or truing speed, the manually operable control lever 70 is shifted from full line position into the broken line position 70a which rocks the gear segment 67 in a counterclockwise direction which, through the gear segment 66, the shaft 61, and the yoked member 60, moves in a clockwise direction to shift the clutch member 55 toward the left (Fig. 2) so that the clutch teeth 56 engage the clutch teeth 57 to form a direct driving connection between the shaft 36 and 41.

To facilitate rotation of the grinding wheel 15 15 at a very slow rotative speed below the normal grinding speed, the shaft 36 is provided with a worm 80 which meshes with the worm gear 81. The worm gear 81 is keyed to a transversely arranged rotatable shaft 82 which is journaled in bearings 83 and 84 which are supported in the casing 28. The forward end of the shaft 82 is rotatably supported in a sleeve 85 which is in turn journaled in bearings 84 supported in the casing 28. A worm 86 is keyed to the rotatable bushing 85, said parts being arranged so that the worm 86 and its supporting bushing 85 may rotate independently of the shaft 82. The worm 86 meshes with a worm gear (not shown) which is supported on a longitudinally extending shaft 87. The shaft 87 is journaled in bearings 88 and 89 supported in the casing 28. A sprocket 90 is keyed to the shaft 87 and is arranged to transmit its rotative power through a link chain 91 to a sprocket 92 which is keyed to the periphery of the rotatable sleeve 78.

The worm 86 is arranged so that it may be readily clutched or declutched from the shaft 82. A clutch member 93 is slidably keyed on the shaft 82 and is provided with clutch teeth 94 which are arranged to engage clutch teeth 95 formed integrally on the end of the worm 86. A yoked member 96 is supported on the end of a slidably mounted actuating rod 97. The rod 97 is journaled in a bearing 98 fixedly mounted relative to the casing 28. The yoked member 96 has integral shoes which engage a groove 99 formed in the periphery of the clutch member 93 so that endwise movement of the rod 97 serves to throw the clutch teeth 94 into engagement with the clutch teeth 95 so that rotary motion of the shaft 82 will be transmitted to rotate the worm 86 or to move the clutch teeth into a disengaged position (Fig. 2). The clutch member 93 is normally held in a disengaged position by means of a spring 100 which surrounds the rod 97 and is interposed between the bearing 98 and a collar 101 which is mounted on the rod 97. The clutch shifting rod 97 may be actuated manually to throw the clutch member 93 into engagement with its clutch teeth 94 engaging the clutch teeth 95 so as to transmit a rotary motion to the worm 86. As illustrated (Fig. 2), a flexible cable 102 is connected by means of a stud 103 with the projecting front end of the clutch shifting rod 97. The cable 102 passes over rotatably mounted grooved idler pulleys 104 and 105 which are supported by studs 106 and 107, respectively. The studs 106 and 107 are supported in brackets which are fixedly mounted on the housing 110. A slidably mounted actuating knob 108 is connected to the forward end of the cable 102. A locking screw 109 is provided for locking the actuating knob in a forward position to hold the clutch member 93 in engagement when desired.

Spindle reciprocating mechanism

In either a plunge-cut grinding operation or a finishing operation where the grinding wheel 15 is held stationary or rotated at a very slow speed, it is desirable to provide a grinding wheel spindle reciprocating mechanism whereby the grinding wheel spindle 16 may be reciprocated axially within its bearings 17 and 18. As illustrated in the drawings, a wheel spindle reciprocating mechanism is contained within a housing 110 which is mounted on the upper portion of the wheel slide 11. An eccentric 111 is formed integral with a rotatable sleeve 112. The sleeve 112 is rotatably journaled in bearings 113 supported in housing 110. The sleeve 112 is preferably drivingly connected with the shaft 82 by means of a key 114, thus forming a telescopic driving connection between the shaft 82 and the sleeve 112 which facilitates adjustment of the casing 28 in tensioning the grinding wheel driving belt 44. The eccentric 111 is connected by a connecting rod 115 with a stud 116 carried by an arm 117 which is pivotally supported on a fulcrum stud 118. A frame 119 which is substantially of a C-shaped cross section is formed integral with the arm 117 and is supported at its outer end by fulcrum studs 120 and 121. When the eccentric 111 is rotated by the shaft 82, an oscillating motion will be transmitted by the connecting rod 115 to oscillate the arm 117 and the frame 119 about the fulcrum studs 120 and 121. The opposite sides of the C-shaped frame 119 are provided with substantially vertically extending grooves 122 and 123 which support slide blocks 124 and 125, respectively. The slide blocks 124 and 125 support the trunnion ends 126 and 127 of a rectangularly shaped slide block 128 which is slidably positioned within an elongated slot 129 in a rock arm 130 (Fig. 3). The rock arm 130 is pivotally supported on a shaft 131 which is journaled in suitable bearings in the wheel slide 11. The rock arm 130 is provided with an enlarged ring-shaped portion which surrounds the wheel spindle 16 and pivotally supports a collar 132 which is provided with trunnions 133 and 134 projecting into bearing apertures in diametrically opposite sides of the enlarged portion of the rock arm 130. The collar 132 is supported between the fixed collar 135 and an adjustable thrust collar 136 carried by the wheel spindle 16 and serves to provide an end thrust bearing for the collar 132, said parts being arranged so that when the lever or rock arm 130 is oscillated, a reciprocating movement is transmitted to move the wheel spindle 16 axially within its supporting bearings 17 and 18 to produce a reciprocatory movement of the grinding wheel 15 during an abrading, honing or finishing operation.

It is desirable to provide means for adjusting the length of the reciprocatory stroke of the wheel spindle. For example, in the construction illustrated in the drawings, a reciprocatory stroke varying from zero up to one-eighth of an inch or more may be obtained. A vertically movable yoke-shaped member 138 (Fig. 6) is vertically adjustable by means of a rotatable screw 139. The screw 139 is rotatably journaled in bearings which are fixedly mounted in the housing 110. The upper end of the screw 139 is provided with a bevel gear 140 which meshes with a bevel gear 141 (Fig. 4) supported on the inner end of a rotatable shaft 142, the outer end of which is provided with a manually operable adjusting wheel 143. The vertically adjustable yoke-shaped member 138 is provided with yoke-shaped arms

144 and 145. The arms 144 and 145 surround anti-friction ball bearings 146 and 147, respectively, which are supported on the trunnions 126 and 127 of the slide block 128. When the screw 139 is rotated, the member 138 is moved vertically which serves to adjust the slide block 128 relative to the elongated aperture 129 in the rock arm 130 and at the same time adjusts the slide blocks 124 and 125 relative to the grooves 122 and 123 in the substantially C-shaped frame 119 so that the axis of the trunnions 126 and 127, respectively, may be moved toward and from the axes of the trunnions 120 and 121, respectively, to vary the length of the reciprocatory stroke of the wheel spindle 16. As illustrated in the drawings, the wheel spindle reciprocating mechanism is shown as adjusted to its maximum extent. If it is desired to change the reciprocatory stroke, the screw 139 is rotated by means of the hand wheel 143 to lower the adjustable member 138 which serves to lower the trunnions 126 and 127, respectively, so that they approach the axes of the trunnions 120 and 121, thereby reducing the oscillatory motion transmitted to the rock arm 130 and thus reducing the reciprocatory movement of the wheel spindle 16 and the grinding wheel 15. If the adjustable member 138 is lowered until the axes of the trunnions 126 and 127 coincide with the axes of the trunnions 120 and 121, then no movement will be transmitted to the rock arm 130 and the wheel spindle 16 will be held against reciprocatory movement.

In order that the operator may readily adjust the reciprocating mechanism for a given stroke, a vertically positioned stud 150 is mounted on the member 138. The stud 150 is provided with a graduated scale which is readily visible from the operator's station in front of the machine. A stop screw 151 serves to limit the vertical movement of the stud 150 and the member 138.

The operation of this improved machine will be readily apparent from the foregoing disclosure. Assuming the various mechanisms and adjustments have been previously made, the machine as illustrated in the drawings is set up for a honing or finishing operation with a stationary wheel which is automatically indexed when the wheel slide is moved to its rearward position automatically to present a fresh grinding face for the next operation. The grinding wheel spindle reciprocating mechanism is also operative to oscillate or reciprocate the wheel spindle 16 within its bearings 17 and 18 so as to produce a reciprocatory movement of the grinding wheel 15.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinabove set forth or shown in the accompanying drawings is to be interpreted as illustrative and not in a limiting sense.

I claim:

In a grinding machine having a transversely movable wheel slide, a rotatable grinding wheel, a rotatable spindle therefor, bearings on the slide for said spindle, an electric motor, high speed driving connections between said motor and spindle to rotate the spindle at a normal grinding speed for a grinding operation, a low speed driving connection between said motor and spin-

idle to rotate said spindle at a speed below the normal grinding speed for a finishing operation, means including a clutch to render either the high or the low speed connections operative, means including a second clutch to start and stop said low speed driving connections to facilitate a polishing operation with the wheel stationary, and a wheel spindle reciprocating mechanism

including a rotatable eccentric, direct driving connections between said motor and eccentric to rotate the eccentric at a constant speed, and adjustable lever connections between said eccentric and spindle whereby the spindle is reciprocated at a constant speed through a variable stroke.

CHARLES C. ALVORD.
